(No Model.)

J. M. & O. A. CRANDELL.

CHURN.

No. 389,874.

Patented Sept. 25, 1888.

UNITED STATES PATENT OFFICE.

JAMES M. CRANDELL AND ORLANDO A. CRANDELL, OF NELSON, NEBRASKA.

CHURN.

SPECIFICATION forming part of Letters Patent No. 389,874, dated September 25, 1888.

Application filed March 10, 1888. Serial No. 266,521. (No model.)

To all whom it may concern:

Be it known that we, JAMES M. CRANDELL and ORLANDO A. CRANDELL, citizens of the United States, residing at Nelson, in the county 5 of Nuckolls and State of Nebraska, have invented a new and useful Improvement in Churns, of which the following is a specification.

The invention relates to improvements in 10 churns and the operative mechanism therefor; and it consists in the construction and novel combination of parts hereinafter described, illustrated in the drawings, and pointed out in the claims.

15 In the drawings, Figure 1 is a perspective view of the mechanism embodying the invention. Fig. 2 is a view of the dasher end of the said mechanism. Fig. 3 is a side view of the same, showing the sprocket-wheels and chain.

20 Referring to the drawings by letter, A designates the main frame of the mechanism resting on the base-board a , having feet at its corners provided with casters, so that the machine can be readily moved.

25 a' a' are standards rising from the front or outer end of the base-board, and a'' a'' are uprights connected to the said standards by horizontal side rails.

30 a^3 a^3 are blocks connecting, respectively, the upper and lower ends of said uprights. In its inner or rear end the base-board is provided with a socket-recess, a^4 , in which the base of a churn or ice-cream freezer may be rested.

35 a^5 a^5 are anti-friction rollers having concave peripheries, against which the vertically-reciprocating dasher-rod B rests as it moves upward and downward. The said dasher-rod has the dasher-blades or beaters b b , of ordinary 40 construction, secured to its lower end, and it moves in the wire spring-clasps b' b' , secured to the blocks a^3 , as shown.

The standards a' a' are each made in two sections hinged together at a^6 , so that the upper 45 part of the frame may be turned outward to more easily put a churn in place.

C is a large chain-wheel secured on one end of a transverse shaft, c , that turns in bearings c' , secured to the standards a' above the hinges a^6 , and c' is a crank-handle on the opposite end of the shaft.

D is a smaller sprocket-wheel secured on the corresponding end of the shaft d , journaled in bearings d' , secured to the uprights a'' ; and d'' is a chain connecting the two sprocket-wheels. d'' is a fly-wheel on the end of the shaft d , opposite that to which the wheel D is attached.

E is a crank-arm on the shaft d to the outer side of the wheel D, and having at its free end 60 the outstanding wrist-pin e .

F is an oscillating shaft journaled in bearings f , secured to the standards a' a proper distance above the shaft c , and having on its end, extended beyond the bearing, the crank-arm G, the bifurcated free end of which is connected by the link-rod g with the wrist-pin e on the crank-arm E.

H is a double-armed vertical lever secured at its center upon the center of the shaft F, so 70 that the oscillation of said shaft vibrates the said lever. The upper arm, h , and lower arm, h' , of said lever are provided with eyes h^2 h^3 , in which the looped ends of the straps I I' are respectively engaged. The strap I passes 75 over a roller or pulley, i , depending from the upper block, a^3 , and the strap I' passes below a similar roller or pulley, i' , standing upward from the lower block, a^3 .

J is a sleeve on the dasher-rod B, which 80 sleeve is rendered adjustable by the set-screw j , passing through a tapped opening in the side of the sleeve and impinging on the dasher-rod.

j' are eyes at opposite sides of the sleeve, respectively connected to the adjacent looped 85 ends of the straps I I'.

It is evident that when the shaft c is rotated by means of the crank-handle c' the shaft d and crank-arm E will also be rotated, and the crank-arm G, which is longer than the arm 90 E, will be vibrated, oscillating the double-armed lever H. The oscillation of the lever will, by means of the straps I I', cause the dasher-rod to reciprocate. The dasher-rod can be set the proper height by means of the 95 adjustable sleeve and its set-screw.

J J are brace-rods having their ends bent and hooked into openings in the base-board a , and lower blocks, a^3 , to hold the upper section of the frame down steadily when the churn is 100 in place. They also support the upper section in place.

By the described mechanism the dasher is caused to reciprocate with great force and the power is economically used.

The dasher-rod can be readily attached to 5 and detached from the wire spring-clasps.

Having described our invention, we claim—

1. The combination, with the main frame composed of the base-board a , the sectioned hinged standards a' , the uprights a^2 , the rails 10 joining said standards and uprights, the blocks a'' , and the brace-rods J , having their ends bent and inserted in openings in the base-board a , and lower block, a^3 , so that they support and stay said block and hold the upper section of the frame down steadily, of the anti-friction rollers having concave peripheries attached to said blocks, the wire-spring guide-catches secured to the blocks a^3 , the reciprocating dasher, and the mechanism whereby 15 said dasher is operated, substantially as specified.

2. The combination, with the main frame and the dasher-rod attached thereto by spring-catches, of the double-armed lever secured to 20 a shaft journaled on the main frame, the straps 25

connected to the ends of the arms of said lever, the adjustable sleeve on the dasher-rod having the adjacent ends of said straps secured to it, and the mechanism, substantially as described, whereby said lever is actuated, substantially as specified. 30

3. The combination, with the main frame and the dasher-rod attached thereto by spring-catches, of the shaft F , journaled on the main frame, the double-armed lever H , secured to 35 said shaft, the adjustable sleeve J , the straps I I' , the shafts c and d , the crank-arms E and G , the link-rod g , the sprocket-wheels C and D , the chain d^2 , and the crank-handle c^2 , all constructed and arranged substantially as and 40 for the purpose specified.

In testimony that we claim the foregoing as our own we have hereto affixed our signatures in presence of two witnesses.

JAMES M. CRANDELL.
ORLANDO A. CRANDELL.
